CONVEYOR TROLLEY HEAD ADDRESSING UNIT

Morton A. Weiss, Springfield, and Bernard S. Speckhart, Short Hills, N.J., assignors to White Machine Co., Kenilworth, N.J., a corporation of New Jersey

Filed Apr. 18, 1968, Ser. No. 11,497

Term of patent 14 years

Int. Cl. D15—99

U.S. Cl. D55—1

FIG. 1 is a perspective view of a conveyor trolley head addressing unit showing our new design;

FIG. 2 is a top plan view thereof;

FIG. 3 is a front elevational view thereof;

FIG. 4 is a right side elevational view thereof;

FIG. 5 is a rear elevational view thereof;

FIG. 6 is a left side elevational view thereof; and

FIG. 7 is a bottom plan view thereof.

We claim:

The ornamental design for a conveyor trolley head addressing unit, as shown.
